UNITED STATES PATENT OFFICE.

FRED M. COURSER, OF ROCHESTER, NEW YORK.

DEVICE FOR CLEANING AND TRUING EMERY-WHEELS, &c.

1,078,258.

Specification of Letters Patent. Patented Nov. 11, 1913.

Application filed December 27, 1912. Serial No. 738,902.

To all whom it may concern:

Be it known that I, FRED M. COURSER, a citizen of the United States, and a resident of Rochester, in the county of Monroe and State of New York, have invented a new and Improved Device for Cleaning and Truing Emery-Wheels, &c., of which the following is a specification.

This invention relates to means for cleaning and also truing emery wheels and like articles, and has more especial reference to that class of emery wheels in which the grinding surface of the wheel is disposed at an angle to rather than parallel with the axis of the wheel, such for instance as wheels having their grinding surfaces either conically formed or tapered or lying in a plane vertical to the axis of the wheel.

The object of my invention is to provide a cheap, efficient device for truing and cleaning wheels of the class above indicated and one that may be readily adapted to the above indicated different conformations of wheels and one, also, in which the truing and cleaning surface may be readily renewed.

With these objects in view my invention comprises, in combination with a suitable support therefor, a revoluble shaft and a relatively fixed platen upon one of which members, preferably the revoluble member, the emery wheel to be trued is suitably secured and upon the other of which there is removably secured the cleaning and truing member, the conformation of which is adapted to coöperate with the grinding surface of the wheel to be cleaned and trued. For the cleaning and truing member I may preferably use emery or carborundum paper or cloth, preferably also, in the form of washers removably held in place on the platen by suitably arranged engaging members.

When the surface of the wheel to be trued and cleaned is in a plane at right angles to the axis of the wheel the member for truing and cleaning the same may present a flat surface, and to aid in the cleaning action I preferably secure the emery wheel to be cleaned eccentrically upon the revoluble member. When, however, the grinding surface of the wheel to be cleaned and trued is conical in form I provide a support for the cleaning and truing member adapted to give to the same a correspondingly conical surface, and in this way a portion of the washer-like truing and cleaning mem-

ber is removed so that when the free ends thereof are brought together the cleaning and truing member is caused to present to the wheel a conical surface by being held in place on a suitably conformed platen member to effect the cleaning and truing operation on a correspondingly conformed emery wheel.

It will, of course, be understood that, when the surface of the wheel to be trued and cleaned is of a conical conformation, the emery wheel must be secured concentrically on the revoluble shaft. For this reason I provide the revoluble shaft with a head upon which there is secured a second head carrying a stud for receiving and holding the emery wheel to be cleaned and trued and with this second head angularly adjustable on the first so as to bring the stud for receiving and holding the emery wheel to a position either concentric with or eccentric to the axis of the revoluble shaft.

My invention comprises then in combination with a suitable support therefor, two coöperating elements, one of the elements provided with means for removably securing thereto the emery wheel to be trued and the other adapted to receive and support and to suitably conform a removable cleaning member and a removable cleaning member adapted to be so supported and conformed thereon.

The accompanying drawings illustrating my invention are as follows:

Figure 1 is a side view of the machine with the parts in their inoperative position. Fig. 2 is a view from the left, with reference to Fig. 1, but showing the parts in their operative position. Fig. 3 is a plan view of the annular truing and cleaning member used on the machine when a conically formed wheel, such as shown in Fig. 6, is to be cleaned. Fig. 4 is a plan view of the annular truing and cleaning member used on the machine when a wheel such as shown in Fig. 7 is to be cleaned and shows, also, part of the supporting plate therefor. Fig. 5 is an enlarged plan view of the parts of the machine seen below the line $x-y$ of Fig. 2. Fig. 6 is a sectional view taken along the line x^1-y^1 of Fig. 5 and with all parts below such line removed. Fig. 7 is a sectional view similar to Fig. 6 of the base plate B but taken at right angles to the line x^1-y^1 of Fig. 5. In this figure there is also

shown in section, the supporting plate and truing and cleaning member seen in Fig. 4 and an emery wheel having a flat grinding surface, while in Fig. 6 there is shown an emery wheel having a conical grinding surface and a truing and cleaning member, such as seen in Fig. 3. In Fig. 7 the parts at the lower end of the operating shaft are shown in side elevation.

10 Similar parts are designated by similar reference characters throughout the several figures of the drawings.

Referring to the drawings,—For properly supporting the parts of my device or machine I provide a suitable standard A having at its upper end an arm A¹ on the outer end of which, and formed preferably integral therewith, there is seen a bearing member α to which is secured the removable bearing member α^1 , both of which bearing members are bored out true to receive the shaft R. The bearing members α and α^1 are secured together by screws engaging through ears v on the member α^1 and threaded into corresponding ears v on the member α . The standard A is provided with flanges α^2 having suitable bosses therein for receiving the screws for securing the machine to any suitable table or support w. 25 The member A has, also, an arm α^4 extending forwardly, or to the left with reference to Fig. 1, under the arm A¹ and provided with a cylindrical member α^2 bored out to receive the platen spindle S. The member α^2 is slotted at s to receive the stem g of the handle G engaging therethrough and secured in the spindle S. The spindle S is rotatable angularly to permit the stem g of the handle G to engage through the slot s¹ at the upper end of the cylinder α^2 to hold the spindle S against rotation when in its uppermost position. The hub of the platen B normally rests on the upper end of the cylinder α^2 and the spindle S is held 30 against rotation by the stem g of the handle G engaging in the slot s. The arms A¹ and α^4 are provided with suitable strengthening webs as indicated.

The platen B is conically recessed as seen 50 at b, the conical recess extending at its inner periphery slightly under the outer periphery of the central portion having a flat surface, as seen at b¹, and within the center of which latter there is provided a recess for receiving the stud E later to be explained. There is also provided, as seen in Fig. 7, a flat washer-like member P adapted to be held in place by tapered pins p engaging therethrough and into suitable holes 55 therefor o¹ in the platen B.

Upon the lower end of the shaft R there is provided a suitable head U secured on the shaft R by means of a suitable pin engaging through the hub u¹ thereof. The head U is turned off on its outer periphery

to present a downwardly enlarging conical surface eccentric, however, to the shaft R. Around the coned or tapered outer periphery of this head U there is rotatably secured a correspondingly coned or tapered washer D¹ by means of screws m threaded into the lower adjustable head member D in such a way that this lower head member D is angularly adjustable on the head U. The parts are so conformed that the shouldered stud E threaded into the head D, as seen at e, may be adjusted to a position concentric with the shaft R or eccentric thereto as desired, and held in such adjusted position against angular movement by means of the spring bolt T vertically movable in a boss u on the head U and normally held in its lowermost and locking position with its lower end engaging in one of the holes d therefor in the member D by means of the spring t.

In using my machine, when a conically conformed wheel V is to be trued and cleaned, I provide a washer of emery or carborundum paper or cloth such as seen at C in Figs. 3, 5 and 6 and with a portion of its periphery removed as seen at c in order that by bringing the parts together the washer may be caused to assume a conical conformation. This member C is provided with openings o adapted to receive the tapered pins p when inserted therethrough and into correspondingly suitably disposed and tapered holes o therefor in the platen B. The pins p are seen in place in Figs. 5 and 6 holding the washer C in operative position.

The washer C is inserted in place with the parts seen in the positions as indicated in Fig. 1 and with the stud E adjusted to a position concentric with the shaft R. The platen B is then raised by means of the handle G which is secured in its locking position, indicated in Fig. 2, showing also the positions of the parts when in use for cleaning and truing a tapered or conically conformed emery wheel V with the platen B in its uppermost position and locked against rotary movement by the stem g of the handle G engaging in the slot s¹ therefor, the emery wheel, of course, having been previously secured to the head D by means of the stud E engaging therethrough, while the platen B was in its lowermost position indicated in Fig. 1. When the parts are in adjusted position for truing the wheel, the shaft R is raised somewhat from the position indicated in Fig. 1 to that indicated in Fig. 2 against the action of a spring r engaging around the shaft R and at its lower end against the upper surface of the head U and around the hub u¹ thereof, while the upper end of the spring r engages against a suitable washer r¹ just under the bearing members α and α^1 . The shaft R is provided at its upper end with an arm H having an

upwardly extending handle *h* thereon by means of which the same is rotated carrying with it of course the emery wheel in the process of truing and cleaning the same. After the wheel *V* has been suitably trued the platen *B* is returned to the lowermost position indicated in Fig. 1 and the emery wheel is removed from the stud *E* and is ready for use.

10 In truing and cleaning an emery wheel, such as *V*¹, having a flat grinding surface disposed at right angles to the axis of the wheel a flat platen-like member *P* is secured in place, as indicated in Fig. 7, by means 15 of the pins *p* engaging through holes therefor in the member *P* and into suitably disposed holes *o*¹ therefor in the platen *B*, the holes *o*¹ being preferably disposed between the holes *o* for receiving these same 20 pins *p* when, as already explained, the device is used for truing and cleaning emery wheels *V* having the grinding surface conically conformed or tapered.

For cleaning and truing an emery wheel 25 having its conformation such as seen in Fig. 7, I provide a washer such as seen at *C*¹ in Fig. 4 and which may preferably be of the same diameter as the supporting member therefor *P* and which is also provided with holes *o*¹ correspondingly positioned with the holes *o*¹ in the platen member *B* for receiving the pins *p*, which pins serve to hold the washer *C*¹ in place during the process of truing and cleaning a flat surfaced wheel *V*¹ 30 and they also serve to hold the platen member *P* in place.

When a flat surfaced wheel is to be ground I prefer to adjust the head *D* in such a way that the stud *E* for holding the wheel will be 40 eccentric to the shaft *R* in order to more effectually clean and true the wheel.

What I claim is:

1. A device for the purpose described comprising, two coöperating and relatively rotatable elements; means for supporting the elements permitting their relative rotation and relative movement in the direction of their axes, one of the elements provided with means for removably securing thereto the 45 emery wheel to be treated and the other element adapted to receive, support and suitably conform a flexible cleaning and truing member in operative relation to the wheel to be treated on the first element and a flexible and removable cleaning and truing member 50 adapted to be supported and conformed thereon in operative relation to the wheel to be treated; yieldable means for forcing one of said elements axially toward the other and 55 a stop for limiting the movement of the elements relatively toward each other under the influence of such forcing means, the parts so conformed and coöperating that when the 60 elements are forced toward each other with an emery wheel on one of them and a truing and cleaning member on the other, in the process of treating the wheel, the effort exerted by such forcing means tends to force 65 an emery wheel on one of them and a truing

and cleaning member on the other, in the process of treating the wheel, the effort exerted by such forcing means tends to force the wheel to be treated into engagement with the truing and cleaning member.

2. A device for the purpose described comprising, two coöperating and relatively rotatable elements; means for supporting the elements permitting their relative rotation and relative movement in the direction of their axes, one of the elements provided with means for removably securing thereto the emery wheel to be treated and the other element adapted to receive, support and suitably conform a flexible cleaning and truing member in operative relation to the wheel to be treated on the first element and a flexible and removable cleaning and truing member 70 adapted to be supported and conformed thereon in operative relation to the wheel to be treated; yieldable means for forcing one of said elements axially toward the other and a stop for limiting the movement of the elements relatively toward each other under the influence of such forcing means, the parts 75 so conformed and coöperating that when the elements are forced toward each other with an emery wheel on one of them and a truing and cleaning member on the other, in the process of treating the wheel, the effort exerted by such forcing means tends to force the wheel to be treated into engagement with the truing and cleaning member and means for releasably holding the elements in relative adjustment with the effort exerted by 80 such forcing means tending to force the wheel to be treated against the truing and cleaning member.

3. A device for the purpose described comprising, two coöperating and relatively rotatable elements; means for supporting the elements permitting their relative rotation and relative movement in the direction of their axes, one of the elements provided with means for removably securing thereto either 85 concentrically or eccentrically, as desired, the emery wheel to be treated and the other element adapted to receive, support and suitably conform a flexible cleaning and truing member in operative relation to the wheel to be treated on the first element and a flexible and removable cleaning and truing member adapted to be supported and conformed thereon in operative relation to the wheel to be treated; yieldable means for forcing one 90 of said elements axially toward the other and a stop for limiting the movement of the elements relatively toward each other under the influence of such forcing means, the parts 95 so conformed and coöperating that when the elements are forced toward each other with an emery wheel on one of them and a truing and cleaning member on the other, in the process of treating the wheel, the effort exerted by such forcing means tends to force the wheel to be treated against the truing and cleaning member.

the wheel to be treated into engagement with the truing and cleaning member.

4. A device for the purpose described comprising, two coöperating and relatively rotatable elements; means for supporting the elements permitting their relative rotation and relative movement in the direction of their axes, one of the elements provided with means for removably securing thereto either 10 concentrically or eccentrically, as desired, the emery wheel to be treated and the other element adapted to receive, support and suitably conform a flexible cleaning and truing member in operative relation to the wheel to be treated on the first element and a flexible and removable cleaning and truing member 15 adapted to be supported and conformed thereon in operative relation to the wheel to be treated; yieldable means for forcing one 20 of said elements axially toward the other and

a stop for limiting the movement of the elements relatively toward each other under the influence of such forcing means, the parts so conformed and coöperating that when the elements are forced toward each other with an emery wheel on one of them and a truing and cleaning member on the other, in the process of treating the wheel, the effort exerted by such forcing means tends to force the wheel to be treated into engagement with the truing and cleaning member and means for releasably holding the elements in relative adjustment with the effort exerted by such forcing means tending to force the wheel to be treated against the truing and 35 cleaning member.
